ATTORNEYS.

UNITED STATES PATENT OFFICE.

PHILIP C. P. BOOTY, OF CHICAGO, ILLINOIS, ASSIGNOR TO MICHAEL T. DALEY, OF CHICAGO, ILLINOIS.

RECEPTACLE FOR FACE POWDER AND THE LIKE.

Application filed February 25, 1926. Serial No. 90,473.

My invention relates to receptacles for holding and dispensing face powder and the like in loose form and particularly to a form of device such as that shown in my 5 prior application, Serial No. 10,736, filed February 21, 1925, of which this application is a continuation in part.

It is one of the objects of my present invention to provide in a device of this type 10 a new and improved form and arrangement of parts for filling the receptacle, whereby the operation of inserting the powder may be performed very readily and quickly and whereby the receptacle shall be very efficient 15 under normal conditions for holding the powder ready for convenient use and whereby it shall be capable of use under trying conditions without leakage of the powder, the arrangement of the parts with respect 20 to the filling operation being such as to permit them to cooperate properly with the remaining parts whereby the receptacle can be used effectively for ejecting the desired supply of powder therefrom in the prescribed manner.

It is another object of my invention to provide a construction of this type in which the spring which serves to hold the top cover plate yieldingly in position may also serve 30 for holding in position, or for assisting in holding in position pressed tightly against its seat, the plate which normally covers the opening through which the powder is inserted.

It is still another object of my invention 35 to improve devices of this type in sundry details hereinafter pointed out. The preferred means by which I have accomplished my several objects is illustrated in the drawing and is hereinafter specifically described. That which I desire to cover by this application is set forth in the claims.

In the drawing,—

Fig. 1 is a perspective view of my improved receptacle, including an outer casing within which the receptacle proper is ordinarily carried.

Fig. 2 is a central vertical section through the device shown in Fig. 1.

Fig. 3 is a fragmentary view similar to a portion of Fig. 2, with the outer casing removed, and with the parts in changed position, and illustrating also a portion of a powder puff in position to receive the 55 powder as it is ejected.

Fig. 4 is a view similar to Fig. 2, with the outer casing removed, and showing a modified form of construction; and

Fig. 5 is a view similar to Fig. 4 but showing still another form of construction.

Referring now to Figs. 1, 2 and 3, in which corresponding parts are indicated by the same reference characters,—10 indicates the body of an outer casing preferably formed of metal having a lid 11 of any 60 approved form hingedly connected therewith. As is clearly shown in Fig. 2, the lid 11 is preferably provided with a mirror 12 held in position by a ring 13.

Within the outer casing 10, is mounted 70 the casing proper of my receptacle, being indicated by the numeral 14. The lower end of the casing 14 is closed by a transversely extending plate 15 held in position by a flange on the lower edge of the casing member 14. The plate 15 is provided with a central opening 16 in which is mounted a closure plate 17 which fits within the opening, with an outwardly extending marginal portion overlying the plate 15 about 80 the opening. At its upper end, the casing member 14 is provided with an integrally formed ring portion 18 which tapers downwardly and inwardly, the lower end of the ring overlying a closure plate 19. The 85 plates 17 and 19 are held yieldingly in their operative closing positions by means of a volute spring 20 which is interposed between the plates. The marginal portion of the plate 19 extends laterally a short distance 90 beyond the lower edge of the ring 18 about the periphery of the plate, whereby a ledge or shoulder is provided by such marginal portion adjacent to the ring 18. The lower end of the spring 20 is held in position with 95 respect to the plate 17 by means of solder at one or more points as indicated at 21 in Fig. 2.

As will be appreciated from an inspection of Fig. 2, the plate 19 is movable downwardly against the action of the spring 20 but is held against displacement edgewise from the opening through the ring 18 by reason of its size with respect to the size of the casing 14. That is to say, when the 105 plate 19 is moved into contact with the inner face of the wall of the casing 14 at one side, the opposite side portion of said plate 19 still underlies the tapered ring portion 18 of the casing for completely closing 110

the opening through the ring. The closure plate 17, however, is of a comparatively small size with respect to the size of the casing as a whole, so that it is possible to displace the closure plate 17 edgewise from the opening 16, it being necessary first to elevate the plate 17 against the action of the spring 20. The spring 20 also has a tendency normally to hold the plate 17 in its centered position, but the spring is adapted to yield for permitting sidewise displacement of the plate when a comparatively small force is applied to the plate for that purpose. The arrangement is such that the plate 17 in its operative position effectively closes the opening 16 so as to prevent powder from escaping through the opening under normal conditions. At the same time, the plate can be very easily and quickly displaced edgewise when it is desired to fill the casing with powder. With the plate 17 in operative position, serving to hold the spring 20 in centered position in the casing, the plate 19 is held against the lower end of the ring 18 with sufficient force to prevent the escape of powder between the plate and the edge of the ring. When, however, the plate 19 is lowered against the action of the spring 20, and particularly when the plate is given a quick downward movement, a supply of powder is forced outwardly by pneumatic action between the plate and the lower end of the ring, such powder being carried out by a current of air curling upwardly and inwardly about the outer edge of the plate 19. By reason of the volute form of the spring 20, the plate 19 can be depressed into very close proximity to the plate 17. The form of the spring also serves to assist in breaking up any possible cakes of powder which may have been formed adjacent to the spring. Under normal circumstances, the often repeated actions of the spring 20 prevent the formation of cakes of powder adjacent to the spring.

In Fig. 3, I have shown a powder puff 22 in position upon the plate 19 ready to receive the powder ejected between the ring 18 and the plate 19.

Referring now to Fig. 4, in which the structure is very similar to that above described, 23 indicates the main casing member provided at its upper edge with an integrally formed ring portion 24. A bottom plate 25 is formed integrally with a flange portion 26 which is secured telescopically within the lower end of the casing 23, being held therein by any suitable means not shown. The bottom plate 25 is provided with a central opening 27 which is provided with a closure plate 28 similar to the plate 17 except that it is arranged to extend only partially through the opening 27 so as to permit the casing member 23 to seat properly within an outer casing such as the cas-

ing 10 without loosening the plate 28 with respect to the opening 27. The top closure plate 29 and the spring 30 are similar to the plate 18 and spring 20 above described.

In Fig. 5, I have provided a casing 31 which is shown in the form of a stamping having an integrally formed tapered ring 32 at its upper edge and having a bottom plate 33 also formed integrally therewith. The bottom plate 33 is provided at one side of the center thereof with an opening 34 which is covered by a closure plate 35 which is rotatably mounted in the bottom of the casing 31. The plate 35 is provided with an opening 36 which is adapted to be brought into registry with the opening 34 or is adapted alternatively to be moved out of registry by the rotation of the plate 35, such rotation being effected by the use of a lug 37 formed by any suitable means on the bottom of the plate 35 adjacent to the opening 36. The opening through the ring 32 is normally closed by a closure plate 38 corresponding to the plate 19, the two plates 35 and 38 being held yieldingly in closing position by means of a volute spring 39.

Inasmuch as the normal operation of the devices shown in Figs. 4 and 5 is the same as that above described in connection with the device of Figs. 1, 2 and 3, it is believed to be unnecessary to describe the same further herein. In each case, the arrangement is such that the bottom closure plate can be displaced edgewise very quickly and readily for the filling operation, while at the same time it is adapted to operate effectively when in operative closing position for preventing the escape of powder.

While I prefer to employ one of the constructions as illustrated in my drawing, it will be understood that I do not desire to limit my invention to the details of the construction as illustrated, except as the same may be limited with respect to specific claims thereto.

I claim:

1. A receptacle for face powder and the like, comprising in combination a casing having an opening thereinto, a plate on the inner face of the casing adapted to close the opening and held against displacement edgewise with respect to the opening, a second opening being provided into the casing, a second plate on the inner face of the casing adapted to close said second opening and adapted to be displaced edgewise from the opening for filling the casing, and spring means adapted normally to hold said plates yieldingly in closing position, the arrangement being such that by the inward and outward movements of the first named plate air is forced from the casing through said first named opening for carrying a supply of powder from the receptacle.

2. A receptacle for face powder and the

like, comprising in combination a casing having an opening thereinto, a plate on the inner face of the casing adapted to close the opening and held against displacement 5 edgewise with respect to the opening, a second opening being provided into the casing opposite said first named opening, a second plate on the inner face of the casing adapted to close said second opening and 10 adapted to be displaced edgewise from the opening for filling the case, and spring means adapted normally to hold said plates yieldingly in closing position, the arrangement being such that by the inward and 15 outward movements of the first named plate air is forced from the casing through said first named opening about the edge of the first named plate for carrying a supply of powder from the receptacle.

20 3. A receptacle for face powder and the like, comprising in combination a casing having an opening thereinto, a plate on the inner face of the casing adapted to close the opening and held against displacement edgewise with respect to the opening, a second opening being provided into the casing, a second plate on the inner face of the casing adapted to close said second opening and 25 adapted to be displaced edgewise from the opening for filling the casing, and a single spring adapted normally to hold said plates yieldingly in closing position.

4. A receptacle for face powder and the like, comprising in combination a casing having an opening thereinto, a plate on the inner face of the casing adapted to close the opening and held against displacement edgewise with respect to the opening, a second opening being provided into the casing opposite said first named opening, a second plate on the inner face of the casing adapted 40 to close said second opening and adapted to be displaced edgewise from the opening for filling the case, and a single spring interposed between said plates adapted normally to hold said plates yieldingly in closing position.

5. A receptacle for face powder and the like, comprising in combination a casing having an opening thereinto, a plate on the inner face of the casing adapted to close the opening and held against displacement edgewise with respect to the opening, a second opening being provided into the casing opposite said first named opening, a second plate on the inner face of the casing adapted 55 to close said second opening and adapted to be displaced edgewise from the opening for filling the case, and a volute spring interposed between said plates adapted normally to hold said plates yieldingly in closing position.

6. A receptacle for face powder and the like, comprising in combination a casing having an opening in its top face, a plate

underlying the opening and held against displacement laterally with respect to the opening but movable downwardly bodily with respect thereto, spring means adapted normally to hold said plate yieldingly in 70 closing position, and a second plate held movably in position so that a portion of the plate closes an opening in the bottom of the casing and so that such closure portion is movable laterally away from the opening 75 for the operation of filling the receptacle.

7. A receptacle for face powder and the like, comprising in combination a casing having an opening in its top face, a plate underlying the opening and held against displacement laterally with respect to the opening but 80 movable downwardly bodily with respect thereto, spring means adapted normally to hold said plate yieldingly in closing position, a second opening being provided in the bottom of the casing, and a second plate fitted within said second opening on the inner face of the casing and having a marginal portion extending laterally from the opening, said second plate being movable 85 laterally with respect to the opening for filling the receptacle.

8. A receptacle for face powder and the like, comprising in combination a casing provided with an opening in its upper face 95 in the form of a ring tapered downwardly and inwardly, a plate underlying the ring and extending laterally a short distance beyond the edge of the ring about the margin of the plate and held against lateral displacement with respect to the ring, spring means adapted normally to hold said plate 100 yieldingly in its closing position, and a second plate closing an opening in the bottom of the casing and movable laterally with respect to the opening for filling the casing.

9. A receptacle for face powder and the like, comprising in combination a casing provided with an opening in its upper face in the form of a ring tapered downwardly and inwardly, a plate underlying the ring and extending laterally a short distance beyond the edge of the ring about the margin of the plate and held against lateral displacement with respect to the ring, a second plate 115 closing an opening in the bottom of the casing and movable laterally with respect to the opening for filling the casing, and a single spring adapted normally to hold both of said plates yieldingly in closing position.

10. A receptacle for face powder and the like, comprising in combination a casing provided with an opening in its upper face in the form of a ring tapered downwardly and inwardly, a plate underlying the ring and extending laterally a short distance beyond the edge of the ring about the margin of the plate and held against lateral displacement with respect to the ring, a second plate 125 closing an opening in the bottom of the cas- 130

- ing and movable laterally with respect to the opening for filling the casing, and a volute spring interposed between said plates adapted normally to hold said plates yieldingly in closing position.
11. A receptacle for face powder and the like, comprising in combination a casing having an opening in its top face, a plate underlying the opening and held against displacement laterally with respect to the opening but movable downwardly bodily with respect thereto, spring means adapted normally to hold said plate yieldingly in closing position, and a second plate held movably in position to close an opening in the bottom of the casing and movable laterally with respect to the opening for the operation of filling the receptacle, the arrangement being such that by the inward and outward movements of the first named plate air is forced from the casing through said first named opening for carrying a supply of powder from the receptacle.
12. A receptacle for face powder and the like, comprising in combination a casing provided with an opening in its upper face in the form of a ring tapered downwardly and inwardly, a plate underlying the ring and extending laterally a short distance beyond the edge of the ring about the margin of the plate and held against lateral displacement with respect to the ring, spring means adapted normally to hold said plate yieldingly in its closing position, and a second plate closing an opening in the bottom of the casing and movable laterally with respect to the opening for filling the casing, the arrangement being such that by the inward and outward movements of the first named plate air is forced from the casing through said first named opening for carrying a supply of powder from the receptacle.
13. A receptacle for face powder and the like, comprising in combination a casing provided with an opening in its upper face in the form of a ring tapered downwardly and inwardly, a plate underlying the ring and extending laterally a short distance beyond the edge of the ring about the margin of the plate and held against lateral displacement with respect to the ring, a second plate closing an opening in the bottom of the casing and movable laterally with respect to the opening for filling the casing, and a volute spring interposed between said plates adapted normally to hold said plates yieldingly in closing position, the arrangement being such that by the inward and outward movements of the first named plate air is forced from the casing through said first named opening for carrying a supply of powder from the receptacle.
14. A receptacle of the class described comprising a casing having at its top an inwardly extending perimetrical flange and in its bottom an opening, a plate within the casing and adapted to cover said opening, cover means for the casing and underlying said flange, and yieldable means interposed between the top side of said plate and the underside of said cover means, for the purpose specified.
15. A receptacle of the class described comprising a casing having at its top an inwardly extending perimetrical flange and in its bottom an opening, a plate within the casing and adapted to cover said opening, cover means for the casing and underlying said flange, and a volute spring interposed between said member and said cover means, for the purpose specified.

PHILIP C. P. BOOTY.
